UNITED STATES PATENT OFFICE.

JACK TAYLOR BENNETT, OF GLASGOW, SCOTLAND.

TALKING MACHINE.

Application filed July 5, 1922. Serial No. 572,822.

To all whom it may concern:

Be it known that I, JACK TAYLOR BENNETT, a subject of the King of Great Britain, residing at 25. Queensborough Gardens, 5 Glasgow, Scotland, have invented new and useful Improvements in Talking Machines, of which the following is a specification.

This invention relates to improved means for enabling a number of records to be 10 played automatically in succession on a talking machine.

The object of my invention is to provide improved means whereby the following operations take place automatically:

15 At the end of a record the sound box and stylus are raised and the tone arm carrying the sound box is moved clear of the record to allow of its removal and replacement by a fresh record.

20 The tone arm is then moved back so that the stylus is over the commencement of the record and the sound box is lowered to allow the stylus to rest upon the record. At the end of the record the operations are re- 25 peated.

In carrying out my invention the necessary movements of the tone arm and sound box (except when a record is being played) are all effected by means of a lever which 30 is pivoted to the tone arm, one arm of the said lever resting directly upon a cam driven by an actuating shaft which is automatically driven one revolution at the end of a record by the gramophone or like motor or by a 35 separate motor.

Preferably each record is provided with a groove or ridge leading from the end of the record groove to a small circular groove coaxial with the centre of the record; by this 40 means the stylus and with it the sound box and tone arm are carried at the end of the record towards its centre and a clutch connecting the actuating shaft previously mentioned to the gramophone or other motor, 45 or obviously, if desired, to a separate motor, is automatically put into action and the shaft is driven one revolution thereby.

In order to lift a record (at the end of a piece) clear of the pin on the turntable I 50 employ a pair of pillars or rods arranged vertically one on either side of the turntable, each rod being connected preferably by a chain to the actuating shaft in such a manner that when the shaft is rotated one 55 revolution the rods are also rotated one revolution. On each rod is a pin or cam

which raises the record clear of and away from the turntable pin.

The records to be played are supported on a spiral thread provided on the vertical 60 rods, a record coming clear of the thread and dropping on to the turntable each time the rods are rotated one revolution. The rods may conveniently be connected by a bar having a centering rod which passes 65 through the central hole in each record.

During the whole of these operations the turntable may continue to rotate.

If and when it is desired to use the gramophone in the ordinary manner means may 70 be provided to prevent the cam and magazine rods from being driven.

In the accompanying drawings which illustrate my invention Figure 1 is an underside view, the platform having been removed 75 from its case and turned over, Figure 2 is an elevation, Figure 3 is a plan, Figure 4 is a perspective view, Figures 5 and 6 are detail perspective views, and Figures 7 to 11 are views showing the cam in different 80 positions.

1 is a platform on which the mechanism to be described is mounted. 2 is a tone arm on which a bell crank lever 3 is pivotally mounted in a bearing 4, 5 is a sound box 85 which is carried by the usual goose neck 6 and rests upon one arm of the lever 3. 7 is a turntable driven by a motor indicated at 8 (Figure 4). 9 is the main driving wheel of a separate motor. The second 90 motor is provided with a brake drum or friction disk 10 by means of which the motor may be stopped by an arm 11 pivoted at 12 to a bracket 13 fixed to the platform, and actuated by a spring 14. The main driving 95 wheel 9 gears with a pinion 15 provided with a bevel wheel 16 which gears with a bevel wheel 17 on a shaft 18. Fast with the shaft 18 is a cam 19 fast with which is a disk 20 having in it a slot 21. The end of 100 the spring actuated arm 11 remote from the brake 10 is bent over so as to be adapted to enter the slot 21 in which position the arm is moved by the spring 14 to press upon the brake 10 and prevent the rotation of the 105 driving wheel 9. That arm of the bell crank lever 3 which is remote from the sound box 5 is controlled by the cam 19 and passes through a slot 22 in the platform 1. The arm is also provided with a projection 110 23 adapted when the tone arm is swung towards the centre of the turntable at the end

of the record to engage a cam 24 on the spring arm 11 in such a manner as to depress the spring arm out of engagement with the slot 21.

5 In operation at the commencement of a record the lever 3 is in the position shown in Figure 7. As the piece is played the tone arm 2 travels in the ordinary manner towards the centre of the turntable carrying 10 with it the lever 3 until the lever 3 has reached the position shown in Figure 8. In this position the projection 23 on the lever 3 comes against the cam 24, lowers the end of the arm 11 out of the slot 21 in the disc 20 and so moves the arm 11 away from the brake 10 thus permitting the motor to start its main driving wheel 9 driving the shaft 18 through the pinion 15 and bevelled wheels 16, 17. As the shaft 18 rotates the cam 19 15 thereon tilts the lever 3 and on further rotation of the cam a spiral projection 25 thereon moves the lever 3 in an axial direction as shown in Figure 9. Further rotation of the cam 19 moves and retains the 20 lever 3 in the position shown in Figure 10 in which position the tone arm and sound box are clear of the record and turntable 7. A record is then removed and replaced by 25 a fresh record by mechanism which will be described hereafter. As soon as the record has been replaced by a fresh one the lever 3 is brought by a spiral projection 26 on the cam 19 to the position shown in Figure 11 bringing the tone arm 2 and sound box 5 30 with it to a position in which the stylus of the sound box 5 is above the commencement of the fresh record. Further rotation of the cam 19 allows the bell crank lever to tilt and lower the stylus on to the record. 35 The cam 19 has now returned to the position shown in Figure 7, that is, the cam has been rotated through one revolution and the end of the spring arm 11 is once more in line with and rises into the slot 21 in the disc 20, thus allowing the spring arm 11 to press 40 upon the brake 10 and stop the motor.

The magazine for supporting the records comprises a pair of rods 27 arranged on either side of the turntable 7. Each rod 27 45 has on it a spiral projection or thread 28 on which the records are supported, and is provided with a preferably padded buffer 29 and with a cam 30 which is adapted to pass underneath a record on the turntable 7 and 50 lift it clear of the central pin with which the turntable is provided, and deliver it to a roller 31. Each rod 27 is provided at its 55 lower end with a sprocket wheel 32 which is connected by a chain 33 to a sprocket 60 wheel 34 which has fast on it a bevel wheel 35 in mesh with a bevel wheel 36 fast with a sleeve 37 which is rotatably mounted on the shaft 18. The chain 33 passes round 65 pulleys 38 in order to drive the two rods 27 in opposite directions. Slidably mounted

on the shaft 18 is a disc 39 having thereon a pin 40 which can be moved into or out of engagement with a slot 41 in a disc 42 fast with the sleeve 37 on which the bevel wheel 36 is mounted by clutch forks 43 carried by 70 a spindle 44 and actuated by a hand lever 45.

In operation, if the pin 40 is in engagement with the slot 41, the rods 27 are rotated one revolution when the cam 19 is rotated one revolution, and the records are thereby 75 gradually lowered on the threads 28. The record which has just been played is removed from the turntable 7 by the cams 30 when the tone arm 2 and sound box 5 are clear of the said record. The lowest record 80 comes clear of the end of the thread 28 and falls on to the buffers 29. This record is then dropped on to the turntable 7 when the cut away portion of the buffers 29 come opposite to the record and the tone arm and 85 sound box are moved into position as previously described.

If it is desired that a record should be repeated the pin 40 is moved out of engagement with the slot 41 by the hand lever 45 90 in which case when the record is finished the cam 19 raises the sound box 5 and moves the tone arm 2 clear of the record, back again so that the stylus of the sound box 5 is above the beginning of the record and lowers the 95 sound box into playing position again.

What I claim is:—

1. In a talking machine adapted to play automatically a number of records in succession, the combination of a turntable, 100 means for rotating the turntable, a tone arm, a sound box pivotally mounted thereon, a single lever pivoted to the tone arm, a cam, and means adapted to rotate the cam at the end of a record, one end of the lever supporting the sound box and the other end engaging the cam, said cam formed to first raise the sound box through said lever, then move it positively to a position clear of the record and turntable, then hold it stationary during 105 the changing of a record, and finally drop it into position to engage the new record in starting position.

2. In a talking machine adapted to play automatically a number of records in succession, the combination of a turntable, 110 means for rotating the turntable, a tone arm, a sound box pivotally mounted thereon, a single lever pivoted to the tone arm, a cam, and means adapted to rotate the cam at the end of a record, one end of the lever supporting the sound box, and the other end of 115 the lever engaging said cam and being positively moved thereby to first raise the sound box and then move the tone arm to starting 120 position.

3. In a talking machine adapted to play automatically a number of records in succession, the combination of a turntable, 125 means for rotating the turntable, a tone arm,

a sound box pivotally mounted thereon, a single lever pivoted to the tone arm, a cam, means adapted to rotate the cam at the end of a record, and means carried by the lever for initiating the operation of said means, one end of the lever supporting the sound box and the other end of the lever engaging said cam and being positively moved thereby to first raise the sound box and then move 10 the tone arm to starting position.

4. In a talking machine adapted to play automatically a number of records in succession, the combination of a turntable, means for rotating the turntable, a tone arm, 15 a sound box pivotally mounted thereon, a single lever pivoted to the tone arm, a cam,

means adapted to rotate the cam at the end of a record, and means carried by the lever for initiating the operation of said means, one end of the lever supporting the sound 20 box and the other end engaging said cam, said cam formed to first raise the sound box through said lever, then move it positively to a position clear of the record and turntable, then hold it stationary during the 25 changing of a record, and finally drop it into position to engage the new record in starting position.

In testimony that I claim the foregoing as my invention I have signed my name this 30 23rd day of June, 1922.

JACK TAYLOR BENNETT.
